UNITED STATES PATENT OFFICE.

MARGUERETTE IRENE WELLS, OF OKLAHOMA, OKLAHOMA.

CUFF FOR SHIRTS.

1,250,400.

Specification of Letters Patent. Patented Dec. 18, 1917.

Application filed October 24, 1916. Serial No. 127,329.

To all whom it may concern:

Be it known that I, MARGUERETTE IRENE WELLS, a citizen of the United States, residing in Oklahoma city, in the county and State of Oklahoma, have invented certain new and useful Improvements in Cuffs for Shirts, of which the following is a specification.

This invention relates to cuffs of the class in which provision is made for substituting a clean part of the cuff for a soiled part thereof. Often a shirt is rendered unusable because of a premature soiling of the cuffs while the remainder of the shirt remains "sweet and clean," but by providing duplicate cuffs for each sleeve of the shirt these objections are overcome.

According to my invention the sleeves of the shirt are provided with cuffs of such construction that when one part is soiled it may be covered or tucked away in such manner as to be entirely concealed and to expose a fresh, clean cuff of the same size and general appearance as that originally exposed.

In the accompanying drawing,

Figure 1 is a perspective view of part of a shirt sleeve with my improvements applied.

Fig. 1^a is a section on the line 1^a—1^a of Fig. 1, illustrating how the material for the cuff is first folded and attached to the sleeve.

Fig. 2 shows a section on the line 2—2 of Fig. 1.

Fig. 3 is a perspective view showing the sleeve and cuff opened to illustrate more clearly the construction.

Fig. 4 shows a section on the line 4—4 of Fig. 3.

Fig. 5 is a view similar to Fig. 1, but showing the changed condition of the cuffs.

Fig. 6 is a section on the line 6—6 of Fig. 5.

Fig. 7 is a view of the interior of the cuff and sleeve shown in Fig. 5.

Fig. 8 is a section on the line 8—8 of Fig. 7.

I have shown my invention applied to the sleeve of a negligee or soft shirt for which my improvements are especially designed. The shirt sleeve A is open at a as usual, and to the outer end of the sleeve the duplex cuff is attached in the manner shown.

As indicated in Fig. 1^a the two edges of two thicknesses of material b are attached at b' to the sleeve to form the inner cuff blank. The outer cuff blank comprises two thicknesses of material c, c', the edge of one part being attached at c^a to the sleeve while the other edge c^b is left free.

The material is doubled at b^a, c^a. This forms a closed pocket between the layers b and an open pocket between the layers c, c'.

The cuffs are not used in the condition shown in Figs. 1^a, 3 and 4, but when folded along the line x—x of Figs. 1^a, 3 or 4 they will assume the condition shown in Fig. 1 in which condition they may be worn.

Cuff buttons may be applied through the button holes d.

When a clean, fresh cuff is needed it may be obtained by placing the part b within the pocket formed between the parts c, c', and then folding the cuffs in the manner shown in Figs. 5 to 8, the part b being at this time entirely concealed.

The cuffs are very easily applied to a sleeve, may be easily changed and readily laundried.

I claim as my invention—

1. A shirt sleeve provided with a reversible cuff, said cuff comprising an inner part constituting a complete cuff, and an outer part constituting a complete cuff having a pocket adapted to receive the inner part.

2. A shirt sleeve provided with a cuff, said cuff comprising a part provided with a pocket extending the entire depth thereof, and another part adapted to enter said pocket.

3. A shirt sleeve provided with a cuff comprising a part provided with a pocket and a part adapted to enter said pocket, the two parts being folded upon themselves with one part within the pocket of the other part.

4. A reversible four-ply cuff for shirts, said cuff comprising an inner two-ply cuff, and an outer two-ply cuff having a pocket to receive said inner cuff.

5. A reversible cuff for shirts, said cuff comprising an inner and an outer cuff of substantially the same size, one of said cuffs having a pocket formed therein for the reception of the other.

6. A reversible cuff for shirts, said cuff comprising an inner and an outer cuff of substantially the same size, one of said cuffs

having a pocket formed therein for receiving and completely inclosing the other of said cuffs.

7. A reversible cuff for shirts, said cuff comprising a pair of overlapping members having a common line of attachment to the shirt, one of said members being provided

with an opening adjacent the line of attachment for the reception of the other of said members.

10

In testimony whereof, I have hereunto subscribed my name.

MARGURETTE IRENE WELLS.
